(57) **CLAIM**

The ornamental design for an industrial printer, as shown in the accompanying drawings and described above.

DESCRIPTION

FIG. 1 is a first perspective view of an industrial printer showing a new design;

FIG. 2 is another perspective view thereof;

FIG. 3 is a front elevation view thereof;

FIG. 4 is a right elevation view thereof;

FIG. 5 is a rear elevation view thereof;

FIG. 6 is a left elevation view thereof;

FIG. 7 is a top plan view thereof; and

FIG. 8 is a bottom plan view thereof.

FIG. 9 is a perspective view of another embodiment of an industrial printer showing a new design;

FIG. 10 is another perspective view thereof;

FIG. 11 is a front elevation view thereof;

FIG. 12 is a right elevation view thereof;

FIG. 13 is a rear elevation view thereof;

FIG. 14 is a left elevation view thereof;

FIG. 15 is a top plan view thereof; and

FIG. 16 is a bottom plan view thereof.

FIG. 17 is a perspective view of another embodiment of an industrial printer showing a new design;

FIG. 18 is another perspective view thereof;

FIG. 19 is a front elevation view thereof;

FIG. 20 is a right elevation view thereof;

FIG. 21 is a rear elevation view thereof;

FIG. 22 is a left elevation view thereof;

FIG. 23 is a top plan view thereof; and

FIG. 24 is a bottom plan view thereof.

FIG. 25 is a perspective view of another embodiment of an industrial printer showing a new design;

FIG. 26 is another perspective view thereof;

FIG. 27 is a front elevation view thereof;

FIG. 28 is a right elevation view thereof;

FIG. 29 is a rear elevation view thereof;

FIG. 30 is a left elevation view thereof;

FIG. 31 is a top plan view thereof; and,

FIG. 32 is a bottom plan view thereof.

(Continued)

All broken lines illustrate unclaimed portions of the industrial printer and form no part of the claimed design.
